UNITED STATES PATENT OFFICE.

JAMES B. LADD AND DAVID BAKER, OF HAVERFORD, PENNSYLVANIA.

CASTING-MACHINE.

No. 905,194.

Specification of Letters Patent.

Patented Dec. 1, 1908.

Application filed February 7, 1907. Serial No. 356,162.

To all whom it may concern:

Be it known that we, JAMES B. LADD and DAVID BAKER, citizens of the United States, both residents of Haverford, State of Pennsylvania, have invented a new and useful Casting-Machine, of which the following is a specification.

Our invention relates to improvements in apparatus for casting pig metal.

Our object is to provide improved means for casting metal into pigs by a continuous operation.

Our invention comprises improved means for supporting the rotatable molds, improved means for directing the molten metal to the molds; improved means for discharging the metal from the molds to a platform for the gradual preliminary cooling of the pigs by a spray while on said platform and then for delivering the pigs to a submerged platform for the final thorough cooling thereof and then for delivering the pigs from the submerged platform to a conveyer delivering to cars or other desired points.

Our invention also comprises improvements in details of construction.

Referring to the drawings:—Figure 1 is a plan view of our device. Fig. 2 is a side elevation in part section. Fig. 3 is a central section. Fig. 4 is a plan of a portion of the periphery of our device on an enlarged scale. Fig. 5 is an elevation of said periphery. Fig. 6 is a vertical cross section showing a portion of the driving mechanism. Fig. 7 is an elevation of the inner side of a portion of the periphery or ring. Fig. 8 is a plan view of that portion of the driving mechanism shown in Fig. 6. Fig. 9 is a cross-section through the molds on line 9—9 of Fig. 10. Fig. 10 is a vertical section of a mold and associated mechanism transverse to that shown in Fig. 9. Fig. 11 is a detail view of the cam plate and tripping projections. Figs. 9, 10 and 11 are on a scale larger than that of the preceding figures.

Similar numerals refer to similar parts throughout the several views.

Broadly speaking our device comprises an annular structure supported on live rollers 31 properly spaced and supported on a stationary annular track 32 seated in suitable masonry. The annular structure is formed of metal plates and angle irons riveted together and is in the nature of a box girder 59, approximately rectangular in cross section except as to its upper side, which is

downwardly inclined towards the center of rotation. The annular structure or girder 59 is suitably braced by trusses 56. The radially disposed trusses are connected with a central post 58 which is properly stepped and supported on stationary masonry. Secured to the box girder 59 are a series of brackets 39 extending above the box girder and supporting the parallel beams 40. In these parallel beams 40 are journaled the trunnions of the mold members 41, as clearly shown in Figs. 4 and 6. The mold members 41 are provided with the star wheels 45, the arms of which are adapted to encounter the tripper projections 68 and 69, that is, the encounter of the first arm with projection 68 causes the turning of the mold one quarter of a revolution. The encounter of the next arm with the tripper projection 69 causes another quarter of a revolution of the mold member. These mold members are provided with two oppositely disposed mold recesses 60, so that when one recess is in the receiving position, the other will be in the inverted or discharging position. It is therefore necessary to cause a half revolution of the mold member in discharging one mold and bringing the other into the receiving position. Above the mold members 41 are provided the series of shed or deflector members 42, for guiding the metal into the molds and for preventing the spilling of the metal between said molds. The construction of these shed members is clearly shown in Figs. 9 and 10. These shed members are supported on the movable rods 46 and 48 to permit the vertical movement of the shed members for the purpose hereinafter to be described.

The rod 46 projects downwardly below the girder 40, while the shed member has a projection 47, beyond the rod 48. These two projections or extensions are adapted to encounter the stationary cam members 44, as shown in Figs. 10 and 11, for causing the elevation of said shed member 42.

Over the journal bearings of the mold members 41, are provided the hoods 61 to prevent the metal from reaching the same.

Upon the top or inclined surface of box girder 59 is placed the platform 35. This platform is annular in form and inclined similarly to the top of the girder, and rests loosely upon the top of the girder to permit of independent movement due to expansion and contraction.

To the underside of the girder 59 are se-

cured the brackets 50 of a form clearly shown in Fig. 6. Upon these brackets 50 rests an inclined platform 36 similar in form to that of platform 35. Secured also to the 5 underside of girder member 59 is the track 34 adapted to rest in the grooves of the live rollers 31. A similar track 33 is supported on the stationary masonry and supports the live rollers 31. These rollers 31 10 are provided with trunnions journaled in the spacing rings 32 for maintaining the rollers at equal distances around the circumference of the annular tracks 33 and 34.

It is also to be noted that the bracket 50 15 projects downwardly into the annular channel or tank 62.

The rotation of the girder 59 is secured by the operation of pinions 16 which mesh with the annular rack 15 secured also to the underside of the girder 59. The pinions 16 20 are operated by the motors 30, see Fig. 1 through the shaft 29 and train of gears 28, 27, 25, 24, 22, 21, 19 and 17 as shown in Fig. 8. The gears 22 and 24 are mounted on the 25 shaft 23, which is suitably journaled in the stationary framework. The gears 16 are preferably placed at diametrically opposite positions with respect to the box girder 59. The location of the pinions at diametrically 30 opposite sides of the girder secures an even distribution of power and tends to keep the machine central.

The scraper 37 is properly supported by the stationary parts and is adapted to sweep 35 the platform 35 see Fig. 1. Approximate this scraper 37 is the inclined chute 38 leading from the level of the platform 35 to the platform 36 as shown in Figs. 1 and 3. Suitably secured to the stationary structure 40 are the scrapers 51 and 52 adapted to sweep the lower platform 36. Approximate these scrapers are provided the inclined chutes 57 as shown in Figs. 1 and 2. These chutes deliver to conveyers 53 and 54 which project 45 into the pits 63 and deliver to car 55.

The ladle 64 is mounted in any suitable way on a track 65 so that it may be brought into alignment with and made to discharge into the pivotally mounted trough 66 as indicated in Figs. 1 and 2. This trough 66 is provided with the operating handle 67 or other suitable means for operating the same.

The annular main 70 is connected with a suitable source of water supply and connects 55 with the leads 71 which connect with and support the spray pipes 72, each lead pipe 71 is provided with a controlling cock 73. These spray pipes 72 are provided with a series of perforations along the underside 60 thereof so as to send a continuous spray of water over the pigs as the same rest upon the inclined platform 35.

The operation of our device is as follows:—As clearly shown by the number of 65 reductions in the train of gears illustrated

in Fig. 8, the rotation of the girder 59 will be very slow compared with the speed of the motors so that a continuous operation of our device is made possible. As each mold passes into line with the charging trough 66 the metal is poured therein. As will be apparent from an inspection of Fig. 1, the mold is then carried around a sufficient portion of a revolution of the structure to permit of the hardening of the metal therein. The star wheel of the mold then encounters the tripping projections 68 and 69, see Figs. 1, 10 and 11 which cause a half rotation of the mold member 41 as above described. This causes the dumping of the pig onto the platform 35, and leaves the mold member in position for another charge. The pig is now sprayed by the spray pipes 72 above described, and is carried around until it reaches the scraper 57 by which it is swept from table 35 onto inclined chute 38 and delivered to table 36 which is submerged beneath the water contained in the annular tank or channel 62, where it lies beneath the water for a half of rotation or more of the structure when it encounters scraper 51 or scraper 52 by which it is swept from table 36 onto inclined chute 57 which delivers to the conveyer 53 or 54, which carries it to the car 55 or other desirable point. It is to be noted 95 also that the shed or deflector members 42 practically rest upon the top of the rectangular mold members 41, and hence it is necessary upon the rotation of any mold member that two of the superimposing deflector members be raised. This is accomplished by providing the projecting rod 46 and projection 47 shown in Fig. 10 and the coöperating stationary cam members 44. These cam members are so placed, relatively 100 to the lug 68 operating a star wheel 45, that said cam members will be encountered to cause the elevation of the two shed members 42 before and until after the mold member 41 has been inverted.

By the mechanism above described we are able to secure the following desirable results: a continuous and relatively rapid casting of pigs, a gradual preliminary air cooling followed by partial cooling by the spray, 115 and a final complete cooling by submerging, and an automatic discharge of the cold pigs to cars or other desirable points. By the mechanism above described we also accomplish a large output with a minimum 120 amount of manual labor. The providing of two deflectors and conveyers in connection with the submerged platform makes it possible to discharge from one conveyer while a loaded car is being replaced by an empty 125 car for the other conveyer without interrupting the continuous operation of the machine. It is also obvious with the use of two conveyers either that one may be put out of commission for any reason whatever 130

without interfering with the continuous operation of the machine.

What we claim is:—

1. In a casting machine, the combination of an annular rotatable box girder, a plurality of rotatable molds supported thereby and a platform for receiving the pigs discharged therefrom.

2. In a casting machine, the combination of a rotatable structure, a plurality of rotatable molds supported thereby, an annular platform for receiving the pigs for preliminary cooling, a second annular platform located below the first and submerged for receiving the pigs for final cooling and means for discharging the pigs from one platform to the other.

3. A casting machine, comprising an annular box girder, brackets connected with one side only of the girder and a plurality of rotatable molds supported by the brackets.

4. A casting machine, comprising a rotatable structure, a plurality of rotatable molds supported thereby, an annular platform for receiving the pigs delivered from the molds, a submerged platform, a scraper for discharging the pigs from the first platform, and an inclined chute for carrying the pigs therefrom to the submerged platform.

5. A rotating structure, a plurality of rotatable molds supported thereby, two annular platforms, one above the other, supported by the rotating structure, for carrying the pigs, an annular water containing channel for receiving the lower platform and means for transferring the pigs from one platform to the other.

6. A rotating structure, a plurality of rotatable molds supported thereby, two annular platforms for carrying the pigs, one above the other, an annular water containing channel for receiving the lower platform, means for transferring the pigs from one platform to the other, a conveyer and means for delivering the pigs from the lower platform to the conveyer.

7. A rotating structure, a plurality of rotatable molds supported thereby, two annular platforms for carrying the pigs, one above the other, an annular water containing channel for receiving the lower platform, means for transferring the pigs from one platform to the other, two conveyers and means for delivering the pigs from the lower platform to said conveyers.

8. In a casting machine, a rotatable structure, a plurality of radially disposed molds supported thereby, deflector-members superimposing the molds, means for rotating the molds and automatic means for causing the elevation of the deflector members to permit the rotation of said molds.

9. In a casting machine, a rotatable structure, a plurality of radially disposed molds supported thereby, a deflector member span-

ning two adjacent molds and provided with transversely extending end flanges or wings.

10. In a pig casting machine, a rotatable structure, rotatable mold members supported thereby, and a platform for receiving the pigs, removably supported by the rotatable structure.

11. In a pig casting machine, a rotatable structure, rotatable mold members supported thereby and a platform for receiving the pigs, resting directly upon and removably supported by the rotatable structure.

12. In a pig casting machine, a rotatable structure, rotatable mold members supported thereby, two annular platforms, one below the other, each removably supported by the rotatable structure and means for transferring the pigs from one platform to the other.

13. In a pig casting machine, a rotatable structure, rotatable mold members supported thereby, two annular platforms one below the other, each removably supported by the rotatable structure, an annular water containing channel for receiving and submerging the lower platform and means for transferring the pigs from one platform to the other.

14. In a continuously operating pig casting machine, the combination of a rotatable structure, rotatable mold members supported thereby, spraying means whereby the pigs are first subjected to a preliminary partial cooling and submerging means for final complete cooling, before leaving the machine.

15. In a pig casting machine, the combination of a rotatable structure, rotatable mold members supported thereby, an annular track secured to the underside thereof, a similar annular track suitably supported on a stationary foundation, and a plurality of live rollers engaging with and operating between said annular tracks.

16. In a pig casting machine, the combination of a rotatable structure, rotatable mold members supported thereby, an annular track secured to the underside thereof, a similar annular track suitably supported on a stationary foundation, a plurality of live rollers engaging with an operating between said annular tracks, and spacing members for maintaining the rollers in the required relative position.

17. In a pig casting machine, the combination of an annular box girder connected to a central post by trusses, a step bearing for the central post, an annular track supported by stationary foundations and a plurality of live rollers engaging with and operating between the annular track and the box girder, and rotatable mold members supported by the box girder.

18. In a pig casting machine, an annular box girder, means for rotating the same, rotatable mold members supported above the girder, an annular platform resting upon the

girder and beneath the molds for receiving the pigs therefrom, a second platform below said girder and lying without its outer periphery, brackets secured to said girder for supporting the second platform and means for transferring pigs from the upper to the lower platform.

19. In a casting machine, a rotatable structure, a plurality of rotatable molds supported thereby, tripping means for discharging the molds, an annular platform rotating with the molds for receiving the pigs discharged therefrom, and means for discharging a spray of water in the path of travel of the pigs on said platform for partially cooling the pigs.

20. A casting machine, comprising a rotatable structure, a plurality of rotatable molds, tripping means for causing the discharge of each mold at a required point in the rotation of the supporting structure, an annular platform for receiving the pigs discharged from

the molds rotating with said supporting structure, and means for spraying the molds after their discharge on the platform, comprising perforated piping having an annular extension above said platform and adapted to discharge thereon throughout the circumference thereof during the rotation of said platform.

21. A casting machine, comprising a rotating annular box girder structure, a plurality of rotatable mold members supported thereby, each mold member provided with oppositely disposed mold recesses, and tripping means for causing the movement of the mold member a half revolution during each complete rotation of the rotatable structure.

JAMES B. LADD.
DAVID BAKER.
